(57) **CLAIM**

The ornamental design for an automotive tail light, as shown and described.

DESCRIPTION

FIG. 1 is a left side/rear end perspective view of an automotive tail light design in accordance with the present invention, wherein a rear end/right side perspective view is a mirror image thereof; and,

FIG. 2 is a rear end elevation view of the automotive tail light design of FIG. 1.

The broken lines are for illustrative purposes only and form no part of the claimed design.
